CLAIM

The ornamental design for a blender base, as shown and described.

DESCRIPTION

FIG. 1 is a main view of the blender base;

FIG. 2 is a front view of the blender base;

FIG. 3 is a rear view of the blender base;

FIG. 4 is a left side view of the blender base;

FIG. 5 is a right side view of the blender base;

FIG. 6 is a top view of the blender base; and,

FIG. 7 is a bottom view of the blender base.

The broken lines shown in the drawings are for illustrative purposes only and form no part of the claimed design.
